UNITED STATES PATENT OFFICE.

PHILIPPE DE CLAMECY, OF BOSTON, MASSACHUSETTS, ASSIGNOR TO CORONA TYPE-WRITER COMPANY, INC., OF GROTON, NEW YORK, A CORPORATION OF NEW YORK.

TYPE-WRITING MACHINE.

1,317,485.

Specification of Letters Patent. Patented Sept. 30, 1919.

Application filed January 25, 1918. Serial No. 213,700.

To all whom it may concern:

Be it known that I, PHILIPPE DE CLAMECY, a citizen of the United States, and resident of Boston, county of Suffolk, and State of 5 Massachusetts, have invented certain new and useful Improvements in Type-Writing Machines, of which the following is a specification.

The object of the invention is to provide 10 a lightweight typewriting machine containing the usual groups of mechanisms found in the accepted standard typewriting machines, and to simplify the construction of the machine and materially reduce the number 15 of parts in order to lessen the cost of manufacture and produce a small portable machine.

In the drawings, Figure 1 is a longitudinal vertical sectional view of the machine, 20 parts of the operating mechanism being shown in side elevation;

Fig. 2 a horizontal sectional view of the machine;

Fig. 3 a plan view thereof;

25 Fig. 4 a transverse sectional view on the line IV—IV of Fig. 2;

Fig. 5 a transverse sectional view taken through the keyboard and showing one bank of keys;

30 Fig. 6 a detail front elevation, with parts broken away, of the ribbon vibrating mechanism;

Fig. 7 a similar view showing the ribbon vibrator mechanism in side elevation;

35 Fig. 8 a transverse sectional view on the line VIII—VIII of Fig. 6; and

Fig. 9 a detail view of the means for raising the platen carriage to its different case-shift positions.

40 Referring to the various parts by numerals, 1 designates the main frame of the machine which is preferably formed of light rigid material such as aluminum, said frame constituting a keyboard part 2, ribbon-reel

45 supporting parts 3, and the type-bar receiving part 4 located between the ribbon-reel supports and the rear wall 5. The usual pivot wire 6 for the type-bars extends transversely of the type-bar receiving portion of

50 the main frame, and on said pivot wire the type-bars 7 are mounted. Said bars normally extend forwardly from their pivots and are provided with type heads 8 which rest on the type support 9' of the main

55 frame, suitable cushioning means being pro-

vided to receive the type heads when they return to their normal at-rest positions. Mounted on the keyboard frame part 2 are a series of upwardly extending guide tubes 9, said tubes being arranged in parallel transverse lines and constituting banks. The tubes 9 are of different heights, the lower ones being arranged in the first bank and the highest ones being in the rear bank. In each tube is arranged a vertically reciprocable 60 key rod 10 which carries at its upper end a finger key 11. The keys are arranged at a uniform distance above the upper ends of the guide tubes in order that the key stroke will be uniform for the different banks. The 65 lower end of the key rod, within the frame of the machine, is provided with a head 12 which serves as a limiting stop for the upward movement of the key and also carries a transversely extending horizontal pin 13 70 which enters the upper end of a curved slot 14 formed in a type-bar operating lever 15. The levers 15 for each bank of keys are pivoted upon a common pivot rod 16 which extends horizontally and transversely across 75 the keyboard part of the main frame. The slotted portion of the levers 15 extend forwardly and upwardly so that the slot is obliquely arranged with respect to the key rod. Upon the depression of a key the upper 80 slotted portion of the key lever is swung forwardly and downwardly, the portion of the lever below the pivot 16 being forced rearwardly and upwardly. Connected to the lower end of each of the type-bar operating 85 levers is a rearwardly and upwardly extending link 17, the rear end of which is connected to the type-bar near the pivot thereof, as indicated at 18 in Fig. 1. It is manifest that by depressing a key the connected 90 link 17 is thrust upwardly and rearwardly, thereby swinging the type-bar upwardly to bring the type head to the printing point. Connected to the lower end of each of the type-bar operating levers 15 is a tension 100 spring 19. The lower ends of these springs are connected to a horizontal plate 20 which rests on the base of the frame and is adapted to move forwardly and rearwardly in guides 21 formed on the sides of the main frame as 105 shown clearly in Fig. 2. This tension plate 20 may be adjusted forwardly or rearwardly to vary the tension of the springs 19, by means of a threaded rod 22 which passes through a lug 23 on the rear edge of said 110

plate, the forward end of the rod 22 extending through the front wall of the main frame and being provided with an operating knob 24. By rotating the threaded tension-adjusting rod 22 the plate 20 may be moved, thereby simultaneously adjusting the tension of all of the springs 19.

The rear end of each type-bar is extended upwardly and rearwardly to form a universal bar operating cam 25. Extending transversely of the machine directly below the pivot wire 6 is a universal bar 26 on which is mounted a series of rollers 27, one roller for each type-bar. The universal bar operating cams 25 of the type-bars are adapted to engage said rollers to thereby depress the universal bar. The universal bar, at each of its ends, is provided with a depending guide pin 28 which fits within a rigid guide tube 29 mounted on the base of the machine. Surrounding the guide pin 28 is a spring 30 which normally maintains the universal bar in its upper position but allows it to be depressed through the action of the cams 25.

Through the operation of the universal bar the escapement mechanism and ribbon vibrating and feeding mechanism are operated.

The carriage bed comprises two transversely extending tracks 31 and 32 rigidly connected together by depending yokes 33. The tracks are horizontally grooved on their adjacent faces to receive ball bearings 34 which are adapted to be engaged by track surfaces formed on the forward and rear edges of the carriage base plate. The end yokes of the carriage bed are provided with depending posts 35 which are beveled and fit within corresponding beveled guideways 36 formed on the inner surfaces of the sides 40 of the main frame, as shown clearly in Fig. 2. When the carriage bed is in its lower normal position the tracks 31 and 32 rest on the upper edges of the machine frame, as shown in Fig. 1. To lift the carriage bed, 45 and the carriage mounted thereon, for the several case-shift positions, two pairs of eccentrics 37 and 38 are employed. These eccentrics engage a laterally extending foot 39 formed on the lower end of each of the 50 posts 35, as shown clearly in Figs. 1 and 2 of the drawings. The eccentrics 37 are smaller in diameter than the eccentrics 38 so that one set of eccentrics are adapted to move the carriage to one case-shift position, 55 the other set being adapted to move the carriage to its other case-shift position. The pair of eccentrics 38 are mounted upon a horizontal shaft 39 journaled in suitable bearings in the sides of the main frame directly below the post 35. Secured to said shaft near each end thereof is a crank arm 40 which extends upwardly and forwardly as shown clearly in Fig. 1. Connected to the 60 upper end of each crank arm is a forwardly extending operating rod 41 whose forward

end is connected to the lower end of one of the operating levers 15, said lever being operatively connected to a shift key 42, as shown clearly in Fig. 2. Upon the depression of the shift key 42 the operating rod 70 41 is thrust upwardly and rearwardly, thereby rotating the shaft 39 and causing the eccentrics 38 to move the posts 35 and the connected carriage bed upwardly to the upper-case position. 75

The eccentrics 37 are mounted upon a sectional sleeve 43 which surrounds the shaft 39. This sleeve is divided near its ends, the sections being connected together by means of the crank 44 as clearly shown in Fig. 9, said 80 crank bridging the crank 40 on the shaft 39, as clearly shown in said figure. Connected to each crank 44 is an operating rod 45 which extends forwardly to an operating lever 15, said lever being operatively connected to a shift key 46. It is manifest that upon the depression of the shift key 46 the sleeve 43 will be rotated and the connected eccentrics 37 caused to lift the carriage bed and the platen carriage thereon to the intermediate 90 case position. The platen shift keys are provided with tension springs 19 to return the keys and the eccentrics to their normal at-rest position, and said springs are connected to the tension plate precisely as described with respect to the type-bar operating levers. 95

The platen carriage 47 is provided with the upwardly extending end brackets 48 in which the shaft of the platen 49 is journaled, 100 said shaft being provided with the finger knobs 50 by means of which it may be rotated. The base plate of the carriage is provided with the longitudinal flanges 51 along its front and rear edge, said flanges 105 fitting in corresponding grooves in the carriage ways 31 and 32 and engaging the balls arranged in said ways. Any suitable form of line space device, such as the lever 52 and the pawl 53, may be employed. The 110 lever 52 is journaled upon the shaft of the platen and may be arranged to vibrate between suitable stops; and a suitable spring may be employed to return the line space lever to its normal position. 115

In rearwardly extending brackets 54 a stop bar 55 is pivotally mounted, said bar being notched on its forward side to receive the adjustable stops 56. Adjustably mounted on the rear of the carriage bed is 120 a main stop 57. The stop bar may be rotated to cause the disengagement of the margin stops and main stop by means of the lever 58 pivoted on the platen shaft and connected by a pin-and-slot connection with a 125 crank arm 59 secured to the stop bar. A spring 60 returns the stop bar operating lever to its normal position. A suitable paper feed table 61 is provided, said table carrying feed rolls 62 and being connected to the 130

end frames of the carriage, as clearly shown in Fig. 1. Suitable paper holding fingers 63 and forward feed rolls 64 are connected to a transverse rod which is mounted in 5 brackets secured to the forward edges of the end pieces 48 of the carriage.

The carriage is provided with the usual feed rack 65; and secured to the carriage bed is a carriage feed pawl 66, said pawl being 10 mounted upon a vertical pivot as shown clearly in Fig. 2. Depending from said feed pawl is a yoke 67 between the arms of which the upper portion 68 of a bell-crank lever 69 operates. Said bell-crank lever is 15 pivoted at 70 and is provided with a forwardly extending arm 71 whose forward end engages a slot in the rear end of a horizontal arm 72 rigidly connected to the universal bar. It is manifest that upon the 20 depression of the universal bar the bell-crank lever 69 will be rocked and the feed pawl oscillated. By reason of the provision of the yoke 67 the feed pawl may be moved vertically for the case-shift positions without disengaging its yoke 67 from the upper 25 end of the arm 68 of the escapement operating lever 69.

The two ribbon reels 73 are mounted upon the upper end of vertical shafts 74, said reels 30 being located in a horizontal position on top of the ribbon reel supporting parts 8. The lower ends of the shafts 74 are mounted in bearings secured to the base of the machine frame, and each shaft carries a small 35 beveled pinion 75 within the machine frame, each of said pinions meshing with a large beveled gear 76 mounted on the end of a short shaft journaled in a suitable standard. On the other end of each of said short shafts 40 is mounted a ratchet wheel 77. Rigidly secured to the universal bar are two horizontal arms 78 which carry at their free ends forwardly extending pawl-carrying arms 79 having vertically arranged pawls 45 80 at their forward ends, which pawls are adapted to engage the teeth of the ratchet wheel 77. The arms 79 are pivoted on the ends of the arms 78 and said arms are connected together by a transversely extending 50 rod 81, one end of which extends through the side of the machine frame and is provided with an operating knob. By moving said rod inwardly or outwardly one of the pawls 80 is brought into engagement 55 with its ratchet wheel, the other pawl being withdrawn from engagement with its ratchet wheel, as clearly indicated in the drawings. The pawls 80 are provided with any suitable form of spring to hold them in 60 engagement with their ratchet wheels and to permit the pawls to slip over the ratchet teeth as the universal bar is depressed. It is obvious that the ribbon reels are rotated through the depression of the universal bar 65 and that the direction of movement of the

ribbon may be reversed at any time by moving the horizontal rod 81 to throw one pawl into operation and to disconnect the other pawl from its ratchet wheel.

The ribbon holder and vibrator 82 extends upwardly and forwardly from its pivot 83, which pivot is mounted in vertically slidable bearing blocks 84 mounted in vertical slots 85 formed in depending lugs 86 carried by the forward carriage rail 91. 70 Connected to the pivot 83 and to one of the lugs 86 is a toggle 87 which is adapted to be operated by means of a forwardly extending rod 88 which is provided at its forward end with a knob. It is manifest that by forcing inwardly or rearwardly the rod 88 the toggle will be extended and the ribbon holder and vibrator shifted vertically to bring the lower portion of the ribbon to the printing point. By this means a two-color ribbon may be used. It is obvious that by drawing the rod 88 forwardly the toggle will be operated to lower the ribbon holder and vibrator. Any suitable means may be employed for holding the toggle in its inner position to thereby secure the ribbon holder in position to bring the lower part of the ribbon to the printing point. 85

Connected to the pivot rod 83 of the ribbon holder and vibrator is a rearwardly and downwardly extending vibrator arm 89, to the lower end of which is pivoted an extension piece 90 provided with a cross head 91 at its lower end. Pivoted to the forward end of a bracket 92 is a bell-crank lever 93 100 formed with a slotted arm 94 extending upwardly and forwardly, and with a horizontal slotted arm 95 extending forwardly, as shown clearly in Fig. 1. The arm 94 is tubular and the cross head 91 extends 105 through the slot in said arm so that the extension piece 90 and the slotted arm 94 form an extensible connection between the bell-crank lever 93 and the vibrator arm 89. Extending upwardly from the universal bar 110 is a rigid rod 96, the upper end of which is connected to the slotted arm 95 of the bell-crank lever 93. It is manifest that by depressing the universal bar the ribbon holder and vibrator will be moved upwardly to 115 the printing point through the bell-crank lever 93 and the vibrator arm 89. The parts are slotted as shown in order to permit the carriage bed to be adjusted vertically for the case-shift positions without disconnecting the vibrator arm and the universal bar. 120

What I claim is:

1. A typewriting machine comprising a type bar, a vertically movable key, a link connected to the type bar and extending forwardly therefrom, a vertically arranged pivoted lever connected to said link and formed with a slot in the upper portion thereof, said slot being angular with respect to the vertical part of the lever, and a 125

- pin carried by the key and operating in said slot whereby upon a depression of the key the link will be thrust rearwardly and upwardly to move the type head to printing position.
2. A type bar action comprising a type bar, means for pivotally supporting the type bar adjacent its rear end to move upwardly and rearwardly to the printing point, a rigid link connected at its rear end with the type bar forwardly of the type bar pivot, a vertically arranged lever connected at its lower end with the forward end of said link and having a slotted portion extending forwardly and upwardly from its upper end, means for pivotally supporting said lever intermediate its lower end and said slotted portion, a vertically reciprocable rod having a lateral projection adjacent its lower end engaging in the slot in said lever, and a finger key held to the upper end of said rod.
3. In a typewriting machine, the combination of a frame, a plurality of type bars fulcrumed adjacent their rear ends in the frame, rigid links connected with the type bars forwardly of the type bar pivots and extending forwardly and downwardly in the frame, a plurality of fulcrum rods extending transversely of the frame in the same horizontal plane, a series of levers pivotally supported intermediate their ends on each of said rods and directly connected with the forward ends of said links below said rods, each of said levers having the portion thereof above its fulcrum rod provided with a slot extending forwardly and upwardly relatively to the rod, a plurality of rows of vertically extending tubular guides of different lengths supported in the frame above the upper ends of the slots in said levers, and key-supporting rods slidably held in said guides and provided with lateral projections at their lower ends engaging in the slots in said levers.
4. In a typewriting machine, the combination of a frame, a plurality of type bars fulcrumed adjacent their rear ends in the frame, rigid links connected with the type bars forwardly of the type bar pivots and extending forwardly and downwardly in the frame, a plurality of fulcrum rods extending transversely of the frame in the same horizontal plane, a series of levers pivotally supported intermediate their ends on each of said rods and directly connected with the forward ends of said links below said rods, each of said levers having the portion thereof above its fulcrum rod provided with a

slot extending forwardly and upwardly relatively to the rod, a plurality of rows of vertically extending tubular guides of different lengths supported in the frame above the upper ends of the slots in said levers, rows of key-supporting rods of different lengths slidably held in said guides, pins carried by the lower ends of said key-supporting rods engaging in the slots in said levers, a horizontally adjustable plate slidably held in the frame, and tension springs held to said plate at their forward ends and connected at their rear ends with the lower ends of said levers.

5. A typewriting machine comprising a series of type bars, a series of finger keys, a rigid link connected to each of said type bars and extending forwardly therefrom, a vertically arranged lever connected to each of said links, means slidably connecting the upper end of each of said levers to a finger key, a spring connected to each of said levers, a tension adjusting plate connected to all of said springs, and means for adjusting said plate to simultaneously vary the tension of all of the springs.

6. A typewriting machine comprising a main frame, a carriage, a platen supported in said carriage, means for moving the carriage transversely of the machine for letter spacing, an escapement mechanism, a universal bar, means connecting said universal bar to the escapement mechanism, type bars, a cam on each of said type bars adapted to engage and operate the universal bar, a rigid link connected to each of said type bars and extending forwardly therefrom, a vertically arranged lever connected to said link, a vertically movable key, means slidably connecting said key to the upper end of said lever, and a tension means to return the key and type bar to their normal positions.

7. A typewriting machine comprising a type bar, a rigid forwardly extending link connected to said type bar, a vertically arranged lever connected at its lower end to said link, a vertically reciprocable key, means slidably connecting said key to the upper end of said lever, a spring for returning said key and type bar to their normal positions, a cam formed on the rear end of the type bar, a universal bar adapted to be engaged and operated by said cam, and mechanism adapted to be operated by said universal bar.

This specification signed this twelfth day of January, A. D. 1918.

PHILIPPE de CLAMECY.
